UNITED STATES PATENT OFFICE.

JAMES E. NORMAN, OF ADDICKS, TEXAS.

TRIMMER AND FILER FOR SAWS.

1,220,445.

Specification of Letters Patent. Patented Mar. 27, 1917.

Application filed October 4, 1915. Serial No. 53,908.

To all whom it may concern:

Be it known that I, JAMES E. NORMAN, a citizen of the United States, residing at Addicks, in the county of Harris and State of Texas, have invented certain new and useful Improvements in Trimmers and Filers for Saws, of which the following is a specification.

This invention relates to new and useful improvements in a trimmer and filer for saws, and is particularly designed for trimming and filing gin saws.

The object of the invention is to provide a device of the character described whereby the saws of the ordinary gin may be easily trimmed and filed, the saw teeth being fed automatically as the operation of trimming and filing proceeds.

Another object of the invention resides in the provision of a mechanism whereby an oscillatory or twisting motion will be imparted to the files as they are applied to the saw teeth.

A further object of the invention resides in the provision of a simple inexpensive device of the character described and one which can be easily operated and kept in repair.

With the above and other objects in view the invention has particular relation to certain novel features of construction, operation, and arrangements of parts an example of which is given in this specification and illustrated in the accompanying drawings wherein:—

Figure 1 is a plan view of the device.

Fig. 2 is a side elevation thereof, partly broken away.

Fig. 3 shows a side view of the actuating mechanism for the trimmer knife.

Fig. 4 shows an isometric view of one of the connecting pitmen employed.

Fig. 5 is a sectional view taken on the line 5—5 of Fig. 1, and

Fig. 6 is a perspective view of the trimmer operating mechanism.

Referring now more particularly to the drawing wherein like numerals of reference designate similar parts in each of the figures the numeral 1 refers to the frame whereon the operative mechanism of the device is mounted. Rotatably mounted in suitable bearings near the top end of the frame is the drive shaft 2 to one end of which is secured the crank 3 and to the other end of which is fixed the disk 4. This shaft

has a spur gear wheel 5 fixed thereon which is in mesh with a corresponding spur gear 6 which is fixed on the transverse counter shaft 7, rotatably mounted in suitable bearings in the frame 1. Fixed to the respective ends of the shaft 7 are the disks 8, 8, pivotally connected to which in staggered relation are the pitmen 9, 9. A double bearing member, having the bearings 10, 10, 60 is adjustably mounted upon the frame 1 and slidably mounted in these bearings are the respective file shafts 11, 11, which are pivotally connected to the pitmen 9, 9. It will be observed from an inspection of Fig. 4 65 that the respective ends of the pitman 9 are bent at right angles to the body thereof but said overturned ends are not in parallel relation giving in effect a twisted shape, one end of said pitman being pivoted to 70 the disk 8 and the other to the end of the corresponding shaft 11 with the result that as the shafts 11, 11 are reciprocated through said pitmen an oscillatory or twisting motion will be imparted to said shafts and to 75 the files 12, 12 driven thereby. In actual operation it may be found necessary to also turn the adjacent ends of each of the shafts 11, 11 in order to accentuate this oscillatory 80 movement of the files. The files 12, 12 here- 85 tofore referred to may be secured to the lower ends of the shafts 11, 11 in any approved manner. The lower end of the frame 1 is notched down forming in effect a bearing 13, one side of which is milled out forming a recess or notch wherein rest the dies 14 and 15 secured in place by a wedge shaped bolt 16 which in turn is secured in position by means of the nut 17 threaded onto the projecting end thereof. The upper end of 90 the die 15 is beveled off forming, with the die 14 a tapering notch through which the trimmer knife 18 reciprocates. This knife is secured to one end of the bar 19 which is pivoted to the lower end of the frame 1 95 just above the bearing 13, by means of the bolt 20 which passes through said bar and the frame 1. The end of said bolt adjacent the knife 18 is threaded to receive the nut 21 which when screwed thereon secures said 100 knife in position between the bolt and the shoulder 22 of the bar 19. The outer end of the bar 19 is connected to the disk 4 by means of the link 23, which has a pivotal connection with said bar and an eccentric 110 pivotal connection with said disk. Secured to opposite sides of the lower end of the

frame are the supporting legs 24, 24, whose free ends are bifurcated, forming the arcuate fingers 25, 25, which rest upon the shafting 26 whereon the gin saws are mounted. A U-shaped bolt 27 is pivoted to the side of the frame 1 in alinement with the shaft 2 and fixed upon said shaft is a cam 28 which plays between the arms of said bolts and reciprocates the same back and forth as said shaft is rotated. To the free end of one of the arms of said bolt the upper end of the rod 29 is pivoted, said pivoted end being adjustable by means of the nuts 30, 30. This rod plays through a bearing 31 upstanding from the frame 1 and its forward end is notched to engage with the teeth of the saw successively, during the operation of sharpening same.

In operation the device when applied to the saw to be sharpened stands in a vertical position as shown, being supported upon the legs 24, 24 which in turn are supported by the saw shafts 26. When the shaft 2 is rotated through the crank 3 a reciprocating movement will be imparted to the files 12, 12 through the mechanism just described. The bearings 10, 10 converge toward the saw and the files cross each other as illustrated in Fig. 2, the saw tooth being operated upon resting up close between said files. The twisting movement imparted to the files through the mechanism heretofore described operates to file off the saw teeth to a needle point, which is necessary for saws of this character. The rim of the saw being operated upon rests against the side of the bearing 13 and between the successive partial rotations of the saw it is at rest, the notch between the dies 14, and 15 being in alinement with the throat between the saw teeth. The rotation of the shaft 2 also operates to rotate the disk 4 and to reciprocate the bar 19 and the trimmer knife 18 carried thereby, said knife passing through said throat and trimming the same to a perfect form. The operation of this knife being uniform the

throats between the teeth will be trimmed uniformly, leaving the teeth uniform in length and shape and preparing them for the filing as above described. 50

As the shaft 2 rotates the cam 28 operates to reciprocate the U-bolt 27, which, through the operation of the rod 29 will impart partial rotations to the saw successively thus bringing the teeth one at a time in position to be operated upon first by the trimmer knife and then by the files. 55

What I claim is:

1. In a device of the character described a frame, one end of which is formed into a bearing having a counter sunk seat, a pair of dies in said seat, one of which is beveled forming a notch between said dies, a wedge shaped bolt locking said dies in position, a trimmer blade pivoted to the frame and arranged to reciprocate through said notch and means for reciprocating said blade. 60

2. In a device of the character described a frame, one end of which is formed into a bearing having a seat, a pair of dies in said seat, one of which is beveled forming a notch between said dies, means for locking said dies in position, a trimmer blade pivoted to the frame and arranged to reciprocate through said notch and means 70 for reciprocating said blade.

3. In a trimmer and filer for saws, a frame, a transverse shaft rotatably mounted thereon, a means for rotating the shaft, a cam fixed to said shaft, a reciprocating member pivoted to the frame, a feed rod one end of which is pivoted to said member and the other end of which is adapted to engage successively against the teeth of the saw, said member being arranged to be engaged alternatively by said cam as it rotates whereby the feed rod is operated to feed the saw. 80

In testimony whereof I have signed my name to this specification.

JAMES E. NORMAN.
